UNITED STATES PATENT OFFICE.

ISAK POMPER, OF NEW YORK, N. Y.

SHOPPING-BAG.

1,189,480

Specification of Letters Patent.

Patented July 4, 1916.

Application filed February 11, 1916. Serial No. 77,561.

To all whom it may concern:

Be it known that I, ISAK POMPER, a subject of the Emperor of Austria-Hungary, residing at New York, in the county of New 5 York and State of New York, have invented certain new and useful Improvements in Shopping-Bags, of which the following is a specification.

The present invention relates to shopping 10 bags and has for its object to provide a bag of flexible material which will be durable and at the same time convenient in handling.

With this object in view, my invention 15 consists in the construction, arrangement and combination of parts as hereinafter more fully described and set forth in the appended claim.

One embodiment of my invention is illustrated in the accompanying drawing, in 20 which similar reference characters denote corresponding parts and of which—

Figure 1 is a perspective elevation of my new bag, Fig. 2 is a vertical section thereof on line 2—2 of Fig. 1; Fig. 3 is a cross section on line 3—3 of Fig. 2 and Fig. 4 is a 25 sectional detail of construction.

The main body of the bag *a* is made of 30 flexible material such as oil cloth, leather or the like, and the side walls *a'* and outer bottom *a''* are made of an integral piece, while the end walls *a'''* may be made of like and thinner material and are fastened by stitching or otherwise to the side walls and outer bottom part of the bag. The end walls 35 are somewhat shorter than the side walls and the longitudinal edges of the latter are folded to form tubular pockets *a''* which are open at their ends. Removably mounted in the said pockets are stiffening means, such 40 as wooden rods *b* or the like which can be inserted into the pockets through the open ends thereof and which are secured in position by pins *c* having heads *c'*. The diameter of the heads *c'* is somewhat larger 45 than that of the pockets, so that when the

pins are driven into the wooden rods their heads will abut against the end edges of the pockets and thereby hold the rods in position therein. Each side wall carries a handle *d* made of a leather strap or the like 50 and these handles are movably fastened to the side walls. To this end, I provide two eyelets *e* in each side wall which are arranged in alinement with each other and below the stiffened longitudinal edges of the 55 side walls. The eyelets are of metal or other suitable rigid material and serve to reinforce the edges of the holes cut in the material. The same are preferably of oblong shape and their holes are somewhat larger 60 than the width and thickness of the looped ends of the handles, so as to permit freedom of movement of the latter. These eyelets prevent the tearing of the material which would take place if the handles were 65 stitched or otherwise directly fastened to the side walls instead of through said eyelets.

The inner bottom is formed by a more or less rigid piece *f* of card board or other 70 suitable material of rectangular shape suitably fastened to the inner surface of the outer bottom and whereby the lower ends of the side walls are separated from one another. 75

What I claim and desire to secure by Letters Patent is:

A flexible shopping bag the side walls of 80 which are folded on their upper edges to form tubular pockets, stiffening rods removably mounted in said pockets and headed pins driven into said stiffening rods and adapted to securely hold the latter in position in said pockets.

In testimony whereof I affix my signature 85 in presence of two witnesses.

ISAK POMPER.
